UNITED STATES PATENT OFFICE.

ANTON SAUR, OF FRANKLIN, INDIANA.

IMPROVEMENT IN DOOR-SILLS.

Specification forming part of Letters Patent No. **171,870**, dated January 4, 1876; application filed December 3, 1875.

To all whom it may concern:

Be it known that I, ANTON SAUR, of Franklin, in the county of Johnson and in the State of Indiana, have invented certain new and useful Improvements in Door-Sills; and do hereby declare that the following is a full, clear, and exact description thereof, reference being had to the accompanying drawings and to the letters of reference marked thereon, making a part of this specification.

The nature of my invention consists in the construction and arrangement of a grooved threshold or sill for outside doors to prevent water from being blown in under the door, as will be hereinafter more fully set forth.

In order to enable others skilled in the art to which my invention appertains to make and use the same, I will now proceed to describe its construction and operation, referring to the annexed drawing, in which—

Figure 1 is a plan view of my improved threshold or sill. Fig. 2 is a cross-section of the same, through the line *x x*, Fig. 1.

A represents the door-sill of any suitable shape or form, and made with its upper surface slanting or inclined from the inner side or edge downward toward the outer side or edge. In the center of the sill *A*, on the upper surface, are a series of concentric semicircular grooves, *B B*, the ends of which pass through the outer lower edge of the sill. These semicircular grooves are connected by a number of short cross-grooves, *a a*. On each side

of the semicircular grooves *B* are grooves *C C*, running diagonally, crossing each other, forming diamond-shaped points *b*. These grooves run to a suitable distance from each end of the sill, the remaining portions at the ends, having grooves *D* running downward and inward toward the center, as shown.

These grooves are all made shallow, so that they can be easily swept over, and being connected and running into each other the water will run off easily and quickly without standing in the grooves.

Having thus fully described my invention, what I claim as new, and desire to secure by Letters Patent, is—

1. The door-sill *A*, provided with a series of concentric semicircles, *B*, connected by means of the short cross-grooves *a*, substantially as herein set forth.

2. The door-sill *A*, provided with the concentric semicircles *B*, with cross-grooves *a*, the diagonal grooves *C*, crossing each other, and the inclined grooves *D* at each end, substantially as and for the purposes herein set forth.

In testimony that I claim the foregoing, I have hereunto set my hand this 3d day of November, 1875.

ANTON SAUR.
